METHOD OF MANUFACTURING HIGH
EMISSIVE CATHODES

Bruno Wienecke, Berlin, Germany

Application March 6, 1930, Serial No. 433,846, and
in Germany March 8, 1929

2 Claims. (Cl. 250—27.5)

The manufacture of cathodes for electron valves, and especially multiple valves, by the metal vapour process has hitherto met with various difficulties, including the difficulty 5 created by the production of the emissive layer upon the cathode. The manufacturing process has generally been such that the substance arranged upon the anode was dispersed by heating the anode by means of an eddy current 10 device, the dispersed substance precipitating upon the cathode which, whilst these operations were proceeding, was preferably kept in a warm state. In the case of multiple valves with anode systems of different sizes, it appears that the 15 dispersal cannot be effected in the same manner for the different anodes. The system with the larger anode, i. e. generally the power amplification stage, is heated much sooner and more intensely than the smaller anodes. As a rule, 20 therefore, only the cathode of the power amplification stage is properly covered, while no emissive layer forms on the cathodes of the voltage amplifying stages, because the heat generated in the anodes of the voltage amplifying 25 stages by means of the eddy current device does not suffice to disperse the substances which have been arranged in the pockets of the anodes. If the heating is proceeded with in such manner 30 that the anodes of the voltage amplifying stages, too, may be properly heated, the excessive heat may damage the anode of the power amplification stage. It may happen, too, that the cathode of the latter system is so strongly heated by the 35 excessive heating of the anode that the layer precipitated upon it evaporates.

It might be suggested that to overcome the difficulties a construction of the multiple valve might be adopted in which each system is heated by itself, i. e. independent of the others by a 40 single eddy current generator. This construction is, however, not so simple as it may appear. The construction of an eddy current device suitable for this purpose is also difficult.

The present application proposes a different 45 method attaining the same end by a simpler process. According to the invention the electrode systems without prejudice to their dimensions in electrical respects, are constructed in such a manner that a single eddy current device 50 produces a uniform heating of the systems.

In the simplest case this aim is attained by the anode systems being given the same cross-sectional shape so that the flux encircled by the anodal areas is of a uniform size. If the anodes 55 of the different systems are in electrical and

thermionic respects of the same material and if they are manufactured in the same way, the same eddy current heat will be produced. A gradation of the different systems in electric respects may be effected by an appropriate 60 choice of the length, i. e. the length of the cathode, the grid and the anode.

The valve according to the invention is, however, not limited to this construction. The enclosed flux is also uniform, if, with the same 65 anode material and with the same thermic properties of the anodes, especially in respect of the heat radiation, the cross-sectional areas of the anodes are the same. The shape of the different anodes, thus, may be different. Thus one sys- 70 tem may be flat, the other circular, the third may have a rectangular shape, as long as the cross-sectional areas are of the same size. The measurement of the length is preferably gov- 75 erned by the electric power of the system.

A third group of multi-system and multiple valves is obtained if the cross-sectional areas of the different systems are different and the choice of the metal for the anodes and their properties in thermic respects are made in such a manner 80 that an even heating is produced for the same exciting alternating field.

Figs. 1-3 illustrate each an example of these three different groups, each example having two electrode systems. 85

Fig. 1 shows the cross-section through the vacuum vessel in which two electrode systems with like shapes of cross-section for anodes 2 and 3 are contained. Perpendicularly to the level of the drawing the terminal amplifying stage 3 may, for instance, be longer than the voltage amplifying stage 2. Correspondingly the grid 4 of system 2 and the heating filament 5 may be of a length differing from that of the grid 6 and heating filament 7 of the system 3. 95 There is the further possibility of differing between the grids 4 and 6 and the filaments 5 and 7 in yet other respects according to the requirements of the properties of the system. Thus the grid 4 of system 2 will generally have a 100 larger amplification factor than the grid 6 of system 3 and that grid will, as a rule, have a small amplification factor as, according to experience, the voltage amplification requires a large and the power amplification a small am- 105 plification factor. At 8 and 9 the substances to be evaporated and precipitated on the cathodes 5 and 7 are arranged in pockets of the anode systems 2 and 3.

Fig. 2 also shows a cross-section through the 110

discharge vessel 1 and the systems 2 and 3. The latter differ in the shapes of their cross-sections, but have the same cross-sectional areas, the flux enclosed by the anodes being therefore the same in both cases.

The cross-section through the discharge tube 1 in Fig. 3 shows 2 systems 2 and 3, which are different in the shape and area of their cross-sections and produce the same eddy current heat 10 by an appropriate choice of the material and a suitable determination of the radiation factors.

In the above lines under eddy current device a high frequency induction coil disposed externally the envelope is understood. The electrodes inside the envelope are heated by the high 15 frequency magnetic field of that coil.

I claim:

1. In an electron discharge device, several electrode systems, each of said systems comprising a plate, a grid and a highly emissive cathode, said plates consisting of the same material, having different lengths, a cross-section of the same area and a portion of a reaction mixture attached thereto, which is to be heated by induced currents. 80

2. In an electron discharge device, several electrode systems, each of said systems comprising a plate, a grid and a highly emissive cathode, said plates consisting of the same material, having different lengths, a cross-section of the same area and shape and a reaction-mixture attached thereto, which is to be heated by induced currents. 85 90
